UNITED STATES PATENT OFFICE

131,284

DESIGN FOR AN UMBRELLA OR SIMILAR ARTICLE

Frances Miller, New York, N. Y.

Application March 24, 1941, Serial No. 99,788

Term of patent 3½ years

To all whom it may concern:

Be it known that I, Frances Miller, a citizen of the United States, residing at New York, in the county of New York and State of New York, have invented a new, original, and ornamental Design for an Umbrella or Similar Article, of which the following is a specification, reference being had to the accompanying drawing, forming part thereof, wherein—

I claim:

The ornamental design for an umbrella or similar article, substantially as shown.

FRANCES MILLER.
